US00D889854S

(12) United States Design Patent (10) Patent No.: US D889,854 S
(45) Date of Patent: * Jul. 14, 2020

(54) FABRIC

(71) Applicant: Milliken & Company, Spartanburg, SC (US)

(72) Inventors: Emery Robert Hollar, III, Spartanburg, SC (US); Carma Dunyell Jordan, Fayetteville, NC (US); Karen H. Stavrakas, Greenville, SC (US)

(73) Assignee: MILLIKEN & COMPANY, Spartanburg, SC (US)

() Term: 15 Years

(21) Appl. No.: 29/672,352

(22) Filed: Dec. 5, 2018

(51) LOC (12) Cl. 05-05

(52) U.S. Cl.

USPC D5/20; D5/58

(58) Field of Classification Search

USPC ... D5/11, 21, 26, 30, 41, 43, 47, 48, 52, 53, D5/55, 56, 58, 59, 60, 61, 62, 63, 64, 65, D5/99; D6/582, 588, 589, 597, 619, 602, D6/612, 616, 617, 622; D19/1; D25/138; D32/57
